(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;

FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1;
FIG. 8 is a toe side view of the golf club head of FIG. 1;
FIG. 9 is a top perspective view of another embodiment of a golf club head;

FIG. 10 is a bottom perspective view of the golf club head of FIG. 9;

FIG. 11 is a top view of the golf club head of FIG. 9;
FIG. 12 is a bottom view of the golf club head of FIG. 9;
FIG. 13 is a front view of the golf club head of FIG. 9;
FIG. 14 is a rear view of the golf club head of FIG. 9;
FIG. 15 is a heel side view of the golf club head of FIG. 9; and,

FIG. 16 is a toe side view of the golf club head of FIG. 9. The broken line showing is included for the purpose of illustrating unclaimed subject matter and forms no part of the claimed design.

1 Claim, 14 Drawing Sheets
